UNITED STATES PATENT OFFICE.

FRANK LITTER, OF BROOKLYN, NEW YORK.

TORCH.

1,180,162.

Specification of Letters Patent. Patented Apr. 18, 1916.

Application filed November 26, 1913. Serial No. 803,225.

To all whom it may concern:

Be it known that I, FRANK LITTER, a citizen of the United States, residing at Brooklyn, in the county of Kings and State 5 of New York, have invented new and useful Improvements in Torches, of which the following is a specification.

This invention relates to torches and more particularly to pocket torches, the principal 10 object of the invention being to provide a novel, simply constructed, cheap and durable device which may be conveniently carried in the pocket and which is especially advantageous for obtaining light in small 15 or inaccessible places.

Another object of the invention is the provision of a novel type of burner and retort.

Further objects of the invention will appear as the following description is read in connection with the accompanying drawing, which forms a part of this application, and in which:—

Figure 1 is a side elevation. Fig. 2 is a 25 vertical sectional view therethrough showing the closing cap in dotted lines.

Referring more particularly to the drawing, 1 represents a casing or tank to which is secured a closing cap 2, comprising a 30 low body portion *a* having a concaved or slightly rounded upper surface 13 and a depending flange 14 of less diameter than the body portion said flange being spaced therefrom, and threaded for engagement with 35 the filling opening 1' in the casing 1. Secured in the depending flange is a wire mesh wick covering extending from the flange 14 to the bottom of the casing 1. Mounted centrally of the curved upper surface 13 of 40 the closure cap 2 is a long longitudinally extending burner or wick tube 3, said tube being adapted to extend below the convex surface 13 of the closure cap for a short distance and coöperate with the hollow body 45 portion *a* of said cap to form a gas collecting chamber or pocket 15 adjacent the entrance of the wick within the tube 3. Removably mounted upon the upper end of 50 the burner tube is a burner, generally indicated at 4, consisting of a tube 5 arranged to fit over the burner tube 3 and having a circular series of pin hole apertures 6 through which the gas will be ejected, as will be more clearly understood hereinafter. 55 The upper end of the tube 5 is closed and surrounding the same above and below the

series of apertures 6 are heat conducting disks 7 and 8 which serve to absorb the heat from the flame and cause pressure in the tube 3 and tank 1 by expansion of the 60 gases therein.

The casing 1 is preferably lined with cotton 9 or other suitable absorbent material and a wick 10 is fitted into the tube 3 and extends down into the receptacle 10 so as 65 to conduct the fumes from the gasoline or other similar volatile oil to the burner openings 6.

In practice, casing 1 is preferably provided with a pair of diametrically arranged 70 studs or projections 11 which are adapted to be engaged by bayonet slots formed in the closing cover 12 which is used to protect the burner tube when the device is not in use. In the operation of the device, the 75 receptacle or tank 1 is filled with any suitable type of volatile oil such as gasoline and this is preferably used owing to its comparative cheapness. After the wick and lining have absorbed as much gasoline as 80 they will hold the loose fuel is emptied and the cap 2 applied, while the pocket or gas collecting chamber 15 the greater portion of whose surface is exposed to the atmosphere insures a sufficient and steady flow of moderately heated gas through the wick tube to prevent flickering of the flame, and to 85 avoid the liability of explosion within the reservoir 1 from a super-heated closure cap. By holding a match or other flame beneath 90 the heat conducting flanges the gas in the upper end of the tube may be properly expanded to secure the desired pressure within the tank 1 and cap 2. This pressure will cause the expulsion of the gas through the 95 pin hole openings 6 and when once lighted the light from the flames will constantly generate sufficient pressure to insure an ample feed. A burner of this character is calculated to give a six power candle light 100 when the wick is lowered below the end of the tube but when the wick is raised to make a small gas space the action will be to increase the size of the flame owing to the increased pressure in the small gas chamber 105 in the tube or burner cap 5, while the end of the wick tube within the cap 2 acting in conjunction with the flange upon said cap will prevent the wick from entirely filling the pocket 15 in the cap 2.

No provision has been made for raising or lowering the wick but it will, of course,

be understood that any suitable type of device may be employed for this purpose or the wick may be lowered by pressing the same downwardly with a match.

5. What is claimed is:—

A device of the kind described, comprising a casing, a central inwardly disposed nipple formed upon said casing and providing an opening therein, a cap adapted to 10 close said opening and provided with a threaded collar engaged with said nipple, an elongated upright wick tube connected to said cap and terminating therein, a wire mesh tubular wick holder secured to the 15 collar of said cap and disposed concentri-

cally in said casing and extending so as to engage the bottom thereof, absorbent material completely filling said casing and surrounding the length of said wire mesh wick holder, and a wick securely mounted 20 throughout the length of said wick holder, so as to engage the bottom of said casing, said wick being reduced in length and snugly fitted in said wick tube.

In testimony whereof I affix my signature in presence of two witnesses.

FRANK LITTER.
